UNITED STATES PATENT OFFICE.

JAMES FAZIO, OF VENICE, CALIFORNIA.

DESIGN FOR A DISPLAY STAND.

Application filed January 2, 1924. Serial No. 8,222. Term of patent 7 years.

To all whom it may concern:

Be it known that I, JAMES FAZIO, a citizen of the United States, residing at Venice, in the county of Los Angeles and State of California, have invented a new, original, and ornamental Design for a Display Stand, of which the following is a specification, reference being had to the accompanying drawing, forming a part thereof.

This invention relates to devices used for inclosing machinery and matter to display or simulate the crushing of fruit and the extracting of juice from fruit at a fruit-juice dispensing stand, and more particularly to displays at an orange-juice dispensing stand.

Fig. 1 is a front elevation of a display stand, showing my new design.

Fig. 2 is a side elevation of the stand.

I claim:

The ornamental design for a display stand, as shown.

In testimony that I claim the foregoing as my invention I have signed my name in the presence of two subscribing witnesses.

JAMES FAZIO.

Witnesses:

E. HATTENBACH,
JOSEPH J. FAZIO.
